UNITED STATES PATENT OFFICE.

WILLIAM H. DOBLE AND GEORGE A. ROBINSON, OF QUINCY, MASSACHUSETTS, ASSIGNEES TO PNEUMATIC SCALE CORPORATION, LIMITED, OF QUINCY, MASSACHUSETTS, A CORPORATION OF MAINE.

MACHINE FOR LINING BOXES.

1,247,238.

Specification of Letters Patent. Patented Nov. 20, 1917.

Application filed March 21, 1916. Serial No. 85,720.

To all whom it may concern:

Be it known that we, WILLIAM H. DOBLE and GEORGE A. ROBINSON, both citizens of the United States, and both residing at 5 Quincy, county of Norfolk, State of Massachusetts, have invented a certain new and useful Improvement in Machines for Lining Boxes, of which the following is a specification, reference being had therein to 10 the accompanying drawings.

The invention is specially intended for application to box lining mechanism employed in connection with machines for setting up the cartons before the lining is inserted, then lining the carton, and then presenting the lined carton to package filling mechanism, but the invention is not intended to be limited to be used with either 15 carton setting up mechanism or with package filling mechanism, nor is it intended to limit the application to use in lining that class of boxes which are technically termed cartons, but it may be employed to line 20 boxes of any suitable form of construction 25 to which the invention is adapted. In the specification the word "carton" is intended to include a box of any form.

The invention is an improvement on the invention shown and described in United 30 States Patent No. 1,037,005, dated August 27, 1912, granted to Pneumatic Scale Corporation, Limited, on the application of Hiller & Joplin. In the machine of said 35 patent the lining blank is folded around a reciprocable plunger which serves as a former, and the overlapping edges are glued together, the former then descends into the carton with the lining blank folded around the former and the former then withdraws, leaving the lining within the box. According 40 to the present invention the paper employed for the lining is a prepared wax paper. The blank is folded around the former in much the same way as is done in the machine of said former patent, but in 45 the device embodying the present invention the former is made of metal or some other heat retaining and heat conducting material, and instead of gluing the overlapping edges together means are provided for heating 50 the former, which, in turn, melts or softens the wax contained in the paper of which the lining blank is composed and pressure is applied to said overlapping por-

tions while the wax is thus melted or softened which causes the said overlapping portions to firmly adhere together when the wax stiffens again upon cooling.

The drawings illustrate one form of machine for lining boxes in the manner above mentioned, a portion of the mechanism being like that shown in said Patent No. 1,037,005.

The invention will be fully understood when taken in connection with the accompanying drawings and the novel features thereof will be pointed out and clearly defined in the claims at the close of this specification.

In the drawings, Figure 1 is a side elevation of a machine embodying the invention.

Fig. 2 is a side elevation on a larger scale than Fig. 1 of a portion of the mechanism shown above the bed plate, the driving mechanism and some of the frame work being broken away and the plunger being shown in a more elevated position than in Fig. 1.

Fig. 3 is a front elevation of the parts shown in Fig. 2.

Fig. 4 is a section on line 4-4 of Fig. 3.

Fig. 5 is a rear elevation showing the clutch operating mechanism.

Fig. 6 is a plan view of the flap folding mechanism which is below the platen.

Fig. 7 is a plan view of the rotary carrier which positions the boxes to receive the lining and also of the delivering and transferring mechanism.

Fig. 8 is a sectional view of the forming block.

Fig. 9 is a plan view of the guide mechanism for the plunger in the latter part of its descent.

Fig. 10 is a detail view showing the lining blank after it has been turned up against the two broad sides of the plunger and one pair of the side flaps are folded.

Fig. 11 is a view showing the second pair of side flaps folded over the first pair of side flaps.

Fig. 12 is a view showing the bottom flaps folded up outside of the outer pair of side flaps.

Fig. 13 is a diagrammatic view showing the electric wiring and connections.

Referring now to the drawings, a strip of paper 1 from which the lining blanks

are cut is run from a roll 2, said paper being a prepared wax paper as already mentioned which contains sufficient wax, paraffin, or equivalent substance, which is capable of being softened on its surface by heating so that if two layers are placed together and pressure is applied while the wax is melted and then they are allowed to cool, said two layers will firmly adhere together. The strip runs from the roll 2 and passes off through suitable feed and guide mechanism to a point where a blank of a suitable length is cut from the strip, whence the severed blank is transferred to the mechanism for shaping the lining and inserting it in the box.

In the form of construction shown, the strip passes between a feed roll 3 and loosely mounted presser roll 4, whence it passes between the two flat guides 5, 6 to a position beneath a cutter 7. Said cutter 7 reciprocates vertically so that in its downward stroke it severs that portion of the strip which projects forward beyond the front end of the guides 5, 6. The severed portion forms a blank A of the requisite length for a single box lining. Before the blank is severed from the strip its forward end will be gripped between the feed rolls 8, 9 which carry the severed blank forward between feed tapes 10, 11 which respectively run around the rolls 12, 13. The upper feed tapes 10 run around a forward roll 14 and the lower feed tapes 11 run around a forward roll 15. The upper rolls run in opposite directions from the lower rolls so that the under run of the tape 10 and the upper run of the tape 11 will move in the same direction and carry the severed blank along between them.

Any suitable mechanism may be employed for driving said feed rolls in unison, suitable mechanism therefor being shown in said Patent 1,037,005.

The said feed rolls 8, 9 and 12, 13 are of somewhat greater length than the width of the strip which forms the blank. Instead of having a single tape 10 and a single tape 11 the full width of the blank there is a series of narrow tapes 10 parallel with each other and spaced apart from each other, and also a series of narrow tapes 11 parallel with and spaced apart from each other so as to support a blank properly at different points in its width, the two tapes which are on either side of the middle of both the upper and under series of tapes being spaced apart from each other far enough to allow room for the passage of the forming block or plunger between them.

The lining blank is folded about the plunger 18 which serves as the former, then is carried by the plunger 18 into the carton. The means for heating the plunger will be described hereinafter. The folding opera-

tion is performed at certain stages in the descent of the plunger.

The mechanism for folding the blank about the plunger is similar to that shown in said Patent No. 1,037,005 and briefly described is as follows: Mounted in the space between the two middle tapes 10 are two parallel rolls 19 spaced apart from each other sufficiently to allow the passage of the plunger between them. After the blank has been positioned on the tapes 10-11 centrally over the space between the rolls 19 the plunger 18 descends, its bottom engaging the lining blank, and carrying it down between the two rolls 19 as shown in Fig. 3.

This causes the blank to be folded up against the two opposite sides of the plunger in substantially U-shape, the blank being wider than the plunger so that it extends beyond the edges of the plunger on both sides. The plunger with the blank thus turned up against the two opposite sides descends farther and passes between the two vertical flat guide plates 20. After the plunger with the lining thus folded against its sides has passed down between the guide plates 20 a sufficient distance it stops long enough for the side wings to be folded. The blank being of greater width than the plunger, when the blank is turned up into the U-shape already described, the portion 181 which is turned up against one side of the plunger will have, on each side, a laterally extending portion or wing 182 and the portion 183 which is turned up against the opposite side of the plunger will have laterally extending portions or wings 184. The wings 182 are first turned in against the two opposite sides of the plunger at right angles to the middle portion 181 as shown in Fig. 10 by means of the vertical folder plates 21 shown in Fig. 6. The folder plates 21 are each formed with a foot 211 which engage the side wings b to form triangular folds at the bottom and press them down against die supporting plates 213. Then the other pair of side wings, 184, are folded in from the opposite side so as to overlap the wings b, by means of another pair of vertical folder plates 22 shown in Fig. 6, which swing in from the side opposite to the folder plates 21, thus leaving the blank in the position shown in Fig. 11, with the triangular horizontal projecting double fold 185 at the bottom of each of two opposite edges of the plunger. The folder plates 21 are actuated by the rocker shaft 212 and intermediate connections, and the folder plates 22 are actuated by the rocker shaft 221 and intermediate connections. The farther descent of the plunger carries it down between two parallel rolls 23 which engage the horizontally projecting triangular flaps g and fold them up against the outside of the side flaps as shown in Fig. 12.

The tape roll 13 is mounted on a shaft 25 on which is mounted also a pulley 26. Roll 15 is mounted on shaft 27 on which is also mounted a pulley 28. A pulley 29 is mounted on a shaft 30. A belt 31 passes around the pulleys 26, 28, and 29, thus positively driving the tape rolls 13 and 15. A gear wheel mounted on shaft 25 which carries the tape roll 13 engages with a gear wheel 10 on the shaft which carries the tape roll 12 thus driving said tape roll 12. Said gear wheels are mounted on the opposite ends of the shafts from that shown in Fig. 1 and are not shown in the drawings because they 15 form no part of the present invention. Shaft 42 carries a beveled gear 43 which engages with a beveled gear 44 mounted on shaft 45. Said shaft 45 carries a beveled gear 46 which meshes with a beveled gear 20 47 on shaft 48. Said shaft 48 carries a sprocket wheel 49 around which passes a sprocket chain 50 which also passes around a sprocket 51 on the shaft 30. Mounted on said shaft 30 is a gear wheel 66 which 25 engages with a pinion 67 on shaft 68 which is driven by a pulley 69. Said pulley 69 is driven by any suitable power. It is loose on shaft 68 but may be put into driving connection therewith by a clutch 70 actuated by a lever 71 fulcrumed at 72 and operated by a slidable hand rod 73. See Figs. 1 and 5.

The plunger 18 is rigidly connected with the lower end of a vertical plunger rod 52 whose upper end is connected with the lower side of a cross head 53 which is slidable in guide ways in the upright portions 54 of the frame. A lever 55 is pivotally connected at one end with the cross head 53 by means 35 40 of a link 57, said link 57 having a loose connection with a pin 58 mounted on said lever 55 and having also a loose connection with a pin 59 mounted on the cross head so that by rocking the said lever 55 on a 45 horizontal axis said cross head 53 may be moved up and down in a straight line in its guide ways, thereby reciprocating the plunger 18.

The mechanism for rocking the said lever 50 55 is as follows: Said lever is fulcrumed at its rear end on a stud 60 projecting from the frame and carries intermediate its ends a roll 61 which engages with a cam groove 62 in the side of the gear wheel 66.

55 In order to counterbalance in part the weight of the plunger so that less power will be required to lift the plunger or so that there will be less strain on the cam, one end of a sprocket chain 63 is connected 60 with said lever 55 between the fulcrum point 60 and the connection with the cross head, said chain running up over a wheel 64, and its other end being connected with one end of a spring 65, the other end of said 65 spring being secured to a hook 66 rigidly

connected with the frame. When the plunger descends and the lever 55 rocks down, the spring 66 will be put under tension, and when the lever is ready to rock back in the other direction the contraction of the spring 70 will pull up on said lever, aiding to lift the plunger and help take the strain off of the cam.

The plunger or former 18 as already stated is composed of metal or some other 75 heat retaining and heat conducting material and any suitable means are provided for heating it. The preferred method is to heat it by electricity. In the form of construction shown in the drawings the plunger is 80 provided with the two heating irons 74, 74. These iron heaters transmit heat to the body of the plunger 18. Connected with the irons 74 are the positive and negative wires 76, 77 the wire 76 leading through the cross 85 head 53 and thence to a switch 78.

The wire 77 passes up through a rheostat 79 and thence to the switch 78. The switch 78 is connected by wires 761 and 771 to any suitable source of electric supply. 90

Inasmuch as the cross head 53 is vertically reciprocable, in order to carry the plunger up and down, the electric connection through the cross head must be such as to be adapted to this reciprocable movement of the cross head. Secured to the upright portion of the frame in which the cross head slides is a block 80 of insulating material formed with two vertical grooves. In the bottom of the said grooves respectively are the two contact plates 775 and 765. Mounted on and forming the upper part of the cross head is a block 82 which is apertured horizontally to receive the pins 773 and 763 respectively to which are secured respectively the wires 77 and 76. The pin 773 carries a brush 774 at its opposite end from that to which the wire 77 is secured, and the pin 763 carries a brush 764. The brushes are kept in yielding contact 100 with the plates by springs 85, 86. As the plunger moves up and down said brushes 774 and 764 move in contact with said contact plates 775 and 765. The contact plate 775 is connected with a wire 776 leading to 105 the rheostat 79 from which the wire 777 leads to one pole of the switch 78. 110

The contact plate 765 is connected with a wire 766 which leads to the other pole of the switch 78. 120

A branch wire 778 leads from the wire 776 before it enters the rheostat 79 and is connected at its ends with the contact point 779 which is adapted to be connected by means of a switch 780 with a wire 781 leading to 125 the rheostat.

When the switch 780 is open, the switch 78 being closed, the circuit will be through the entire resistance coil of the rheostat, but when the switch 780 is closed the current 130

will take the line of least resistance and it will branch off through the wire 778 and wire 781 and thence through that portion of the resistance coil which is not cut out by 5 the lever 782, thence through the wire 777 to the switch 78.

When it is desired to heat the plunger through the heating irons 74 the switch 780 is closed. When it is desired to temporarily 10 stop the machine it is important to have the heat reduced somewhat so as not to overheat the irons, and in order to do that the switch 780 is opened so as to throw the current through the entire length of the 15 resistance coil. In order to make sure that the switch is thus opened whenever the machine is stopped temporarily and to provide for any carelessness on the part of the workmen in neglecting to open the switch, means 20 are provided whereby the throwing of the clutch to stop the machine will also open the switch. As already stated, the clutch 70 is operated through the lever 71 and rod 73. Inclosed in a box 91 is a standard type 25 of push button switch represented by 780 in the diagram, Fig. 13, having a push button 92 to close the circuit and a push button 93 to open the circuit through the wires 778 and 781. The button 92 is engaged by a 30 lever 94, fulcrumed at 95. Said lever 94 is engaged by a hook 83 mounted on rod 73.

The push button 93 is engaged by a slide 96 which in turn is engaged by one arm of a bell crank lever 97 whose other arm has a 35 link connection with lever 94. When the said rod 73 is moved in the direction to close the clutch it will also turn the lever 94 in a direction to push in the button 92, thus closing the circuit through the wire 781, 40 and when the rod 73 is moved in the direction to disengage the clutch and stop the machine the lever 94 will be turned so that the bell crank 97 will actuate the push button 93 to open the circuit through the switch 780 45 and cause the current to pass through the entire length of the resistance coil in the rheostat.

The object of having the current automatically reduced when the machine is temporarily stopped is because if the full current is on while the machine is not in operation the heat will increase and heat the former to such an extent that even if the machine is not shut down for more than a 50 few minutes sufficient heat will develop to set the paper on fire and if this is repeated many times it will also ruin the former.

If after the machine has been out of operation for some time, as for instance over 60 night, and it is desired to heat the plunger block quickly before the machine starts up, the hook 83 may be disengaged from the switch 94 by hand, and then the push button 92 may be pushed in to close the circuit 65 through the wires 778, and 781, without

throwing the clutch into engagement with the driving pulley.

When the plunger passes down between the two rolls 23, 23 which fold the triangular portions turned up from the bottom as 70 already described, the wax in the paper already being softened, the pressure of these rolls 23 will be applied not only to the said triangular flat portions but also applied to the full length of the overlapping side portions of the lining, thus causing an adhesion 75 between the said overlapping portions.

After passing between the rolls 23, 23 the plunger in its further descent passes down between the vertical guides 90, said guides 80 preferably being four in number arranged to form a hollow square, said guides being right angled in cross section as shown in Fig. 9 so as to engage the four corners of the plunger with the lining wrapped around 85 it, and these guides keep the overlapping portions from springing apart from each other while the block is descending from the folding level into the box.

It is characteristic of waxed or paraffined 90 paper of the kind described and used in carrying out this invention that when two portions overlap each other while the wax is in a melted or softened condition and slight pressure is applied, the overlapping 95 portions will adhere together and will not adhere to the forming block, hence, when the plunger rises in the continued operation of the machine after the plunger has carried the lining into the carton, it will slip out of 100 the lining.

The cartons may be presented and positioned in any suitable way to receive the plunger or former with the lining blank completely folded and sealed. One form of 105 mechanism for thus presenting and positioning the cartons is fully described in said Patent No. 1,037,005 and it is not deemed necessary to again describe it in detail.

Briefly, it is as follows: A continuously 110 driven belt 101 brings the carton to a rotary carrying mechanism or spider 102 which carries it around ninety degrees to a position beneath the plunger block and after the carton has received the lining the next period 115 of rotation of the spider carries the lined carton around through another rotation to a point at 180° from the point where the spider received the carton and redeposits it on the belt 101 which extends underneath 120 this spider. The spider 102 is mounted on a rotary shaft 103 which is rotated intermittently making a one quarter turn at each period of rotation.

The spider is formed with four radiating 125 arms 104 each carrying a pocket 105 to receive a carton from the belt 101. As the spider rotates, the carton will be carried from the station *a* where it receives the carton from the belt through 90° to station *b* 130

beneath the plunger, ready to receive the plunger with the lining wrapped around it. It comes into this position during the movement of the plunger so as to be there at the 5 proper time.

After the lining has been inserted while the carton is at the station *b* and the plunger has withdrawn, the spider will make another one quarter turn carrying the carton 10 with the inclosed lining around to the third station indicated by *c* and delivered onto the belt 101 which will remove the carton to a suitable place of delivery.

While we have described the invention as 15 applied to a machine in which the forming block is heated, we desire it to be understood that that is only one form of mechanism in which our invention may be embodied. Our invention consists, broadly, in the making 20 of a lining for a box out of paper having a coating of wax or the like, by shaping the blank into a form to fit the interior of the box, with overlapping portions to form joints, and heating the wax or like preparation 25 in the paper sufficiently to melt or soften the wax, and positively causing the overlapping portions at the joints to remain in contact with each other a sufficient length of time for the contacting wax surfaces to 30 adhere together; and it is our purpose that the claims shall be construed as sufficiently broad to cover any mechanism for accomplishing the above result.

What we claim is:

1. In a machine for lining boxes, a former, means for folding a blank about the former to form a lining for a box, means for moving the former with the lining formed thereon into the box, means for applying to the 40 former a heating medium during the operation of the machine, driving mechanism, means for putting the driving mechanism into and out of operative connection with the folding and former actuating mechanism and means whereby the disengagement of the driving mechanism from the folding and former actuating mechanism automatically reduces the heat applying medium without completely cutting off the same.

2. In a machine for lining boxes, a former, means for reciprocating the former, means for folding a lining blank about the former, means for applying a heating medium to the former, means for driving both the former 55 and the folder, means to engage and disengage said driving mechanism with relation to said former actuating and folder actuating mechanism and means whereby the disengagement of the driving mechanism reduces the heat applying medium without entirely cutting off the same, and whereby the engagement of the driving mechanism causes an increase in the heat applying medium.

3. In a machine for lining boxes, a former, 60 means for reciprocating the former, means

for folding a lining blank about the former, means for applying a heating medium to the former, means for driving both the former and the folder, means to engage and disengage said driving mechanism with relation 70 to said former actuating and folder actuating mechanism and means whereby the disengagement of the driving mechanism reduces the heat applying medium and whereby the engagement of the driving mechanism 75 causes an increase in the heat applying medium.

4. In a machine for lining boxes, a former, means for folding a blank about the former to form a lining for a box, means for moving the former with the lining thereon into the box, an electric circuit including therein a heater connected with said former, a resistance coil in said circuit, a shunt circuit through which the current may be made to 80 pass through a portion only of said resistance coil, driving mechanism, clutch mechanism for connecting the driving mechanism with the former actuating mechanism, means for moving the clutch into and out of engagement with the folder actuating and former actuating mechanism, a switch connected with said electric circuit and means actuated by the clutch actuating mechanism whereby when the clutch mechanism is 85 moved into engagement with the folder actuating and former actuating mechanism the 90 said switch is turned to make the electric circuit through the shunt and thereby through only a portion of the coil, and 95 whereby when the clutch is disengaged the said switch is thrown so as to make the circuit through the entire resistance coil and thereby reduce the amount of heat applied to the said former.

5. In a machine for lining boxes, a former, means for applying a heating medium to the former, means for folding a blank about the former to shape the lining, driving mechanism for actuating the folding mechanism, means for putting the driving mechanism into and out of operative connection with the folding mechanism and means whereby the disengagement of the driving mechanism from the folding mechanism reduces 110 the heat applying medium.

6. In a machine for lining boxes, a former, an electric heater for the former, means for folding a blank about the former to shape the lining, driving mechanism, clutch mechanism for connecting said driving mechanism with the folder actuating mechanism, means for actuating said clutch to engage and disengage the driving mechanism with relation to the folder mechanism, and means 120 actuated by said clutch actuating mechanism to vary the electric current through the heater whereby the current is reduced when the clutch is disengaged.

7. In a machine for lining boxes, a former, 125

8

an electric heater for the former, means for folding a blank about the former to shape the lining, driving mechanism, clutch mechanism for connecting said driving mechanism with the folder actuating mechanism, means for actuating said clutch to engage and disengage the driving mechanism with relation to the folder mechanism, an electric circuit through the former having a resistance coil therein, means actuated by said clutch actuated mechanism whereby when the clutch is thrown to disengage the driving mechanism the current will be made to pass through the entire resistance coil and when the clutch is thrown into engagement the current will be caused to pass through only a part of the resistance coil, and means under the control of the operator to at will entirely cut off the electric current or to turn the current through the heater independently of the clutch actuating mechanism and while the clutch is disengaged.

8. In combination with driving mechanism, driven mechanism, clutch mechanism for connecting said driving mechanism with

said driven mechanism, a main electric circuit, a resistance coil in said circuit, a shunt circuit by which the current may be made to pass through a portion only of said resistance coil, means for moving the clutch into and out of engagement with said driven mechanism, a switch connected with said electric circuit, and means actuated by the clutch actuating mechanism whereby when the clutch mechanism is moved to connect the said driving mechanism with the said driven mechanism the said switch is turned to make the electric circuit through the shunt and thereby through only a portion of the resistance coil, and whereby when the clutch is disengaged the said switch is thrown so as to make the circuit through the entire resistance coil.

In testimony whereof we affix our signatures, in presence of two witnesses.
